UNITED STATES PATENT OFFICE

NICHOLAS KOPP, OF PITTSBURGH, PENNSYLVANIA, ASSIGNOR TO KOPP GLASS, INCORPORATED, OF SWISSVALE, PENNSYLVANIA, A CORPORATION OF PENNSYLVANIA

DESIGN FOR AN ADVERTISING SIGN

Application filed April 2, 1931. Serial No. 39,341. Term of patent 7 years.

To all whom it may concern:

Be it known that I, NICHOLAS KOPP, a citizen of the United States, residing at Pittsburgh, in the county of Allegheny and State of Pennsylvania, have invented a new, original, and ornamental Design for an Advertising Sign, of which the following is a specification, reference being had to the accompanying drawings, forming part thereof.

In the drawings:

Fig. 1 is an elevational view of an advertising sign, showing my new design;
Fig. 2 a top plan view thereof; and
Fig. 3 a bottom plan view thereof.

I claim:

The ornamental design for an advertising sign, as shown.

NICHOLAS KOPP.
